UNITED STATES PATENT OFFICE.

DON CURTIS LUCE, OF BOSTON, MASSACHUSETTS.

DRAINAGE AND SEDIMENT-COLLECTING SECTION FOR HOUSE-BOILER CONDUITS.

1,013,031.

Specification of Letters Patent. Patented Dec. 26, 1911.

Application filed November 9, 1910. Serial No. 591,511.

To all whom it may concern:

Be it known that I, DON CURTIS LUCE, of Boston, in the county of Suffolk and State of Massachusetts, have invented certain new and useful Improvements in Drainage and Sediment-Collecting Sections for House-Boiler Conduits, of which the following is a specification.

This invention relates to circulating conduits used to connect a house boiler with the water front or back of an ordinary kitchen range, the boiler being located adjacent to the range and connected therewith by a flow pipe through which water passes from the water front to the boiler, and a return pipe through which the water passes from the boiler to the water front. The boiler is, strictly speaking, a reservoir, since the water is not heated therein, but inasmuch as it is called a "boiler" by the trade, I use that term herein.

It is customary to provide the return pipe with an outlet through which water can be drawn from the system which includes the boiler, the water front and the connecting pipes. Said outlet has heretofore been an ordinary pipe T, two of the branches of which are connected to two alined sections of the return pipe, while the other branch is connected with a cock which controls the outlet through said branch.

My invention has for its object to provide, as a substitute for the T heretofore employed, a section or fitting, adapted not only to drain the water from the system, but also to serve as a receptacle for sediment carried by the water flowing from the boiler to the water front, said sediment being removable by opening the outlet valve of the fitting.

The invention consists in the improved conduit section or T substitute which I will now proceed to describe and claim.

Of the accompanying drawings which form a part of this specification,—Figure 1 represents a side view of a house-boiler and parts of the flow and return pipes which connect the same with the water front; the return pipe being provided with a drainage and sediment-collecting section embodying my invention; Fig. 2 represents a side view of the said drainage and sediment-collecting section, parts of the same being broken away, and Fig. 3 represents a section on line 3—3 of Fig. 2.

Similar reference characters indicate the same or similar parts in all the figures.

In the drawings, 12 represents a house boiler which may be of any suitable construction.

13 represents the flow pipe which connects the water front or back of a range with the upper portion of said boiler, and 14, 14, represent sections of the return pipe which connects the lower portion of the boiler with the water front. Heretofore the sections 14 have been connected with each other by two alined branches of a pipe T, the third branch of which projects downwardly from the return pipe, and is provided with a cock which, when open, permits the withdrawal of water.

In carrying out my invention I provide as a substitute for the T above referred to, a flask 15, which is a hollow casting having at one end a contracted neck 16 adapted to be connected with an outlet controlling cock or valve 17, and at the opposite end an elongated closed wall 18 extending in a direction at right angles with the neck 16. At opposite ends of the wall 18 are formed sockets 19, 19, which are in alinement with each other and therefore extend at right angles with the neck 16, said sockets being adapted to engage the alined pipe sections 14. The neck 16 and the sockets 19 are preferably each provided with an internal screw thread, the thread of the neck 16 being adapted to engage an external thread on the cock 17, while the threads of the sockets 19 are adapted to engage external threads on the pipe sections 14.

By comparing Figs. 2 and 3 it will be seen that the upper end wall 18 is curved to semi-cylindrical form, while the web portions 19 of the sockets are formed as inwardly extending flanges. The inner surfaces of the flanges 19 and the inner surfaces of the upper end wall 18 coact in forming cylindrical internally threaded sockets which are entirely within the area of the flask so that there are no projecting nipples that are liable to be broken or knocked off.

The end wall 18 and the sockets 19 take the place of the transverse or head portion of an ordinary T, and the body portion of the flask below said end walls and sockets, together with the neck 16 formed thereon, take the place of the single arm portion of the T. It will be seen therefore that when the cock 17 is open, water may be drawn from the system as a whole. It will also be seen that the body portion of the flask con-

stributes a receptacle for sediment below the level of the pipe sections 14, said receptacle being of suitable capacity to contain all the sediment likely to be deposited during a considerable period of time.

5 The flask is preferably oblong in cross section so that it has two relatively wide sides and two narrow sides or edges, this form enabling the flask to be supported under the 10 pipe sections 14 without projecting laterally far enough to interfere with an adjacent wall to which the pipe sections may be in close proximity.

15 I claim:—

16 A conduit section of the character described, comprising a flask having at its lower end a contracted neck adapted to be connected with an outlet-controlling cock or valve, said flask having at its upper end

a semi-cylindrical wall extending at right angles with the neck, the flask having inwardly extending semi-cylindrical flanges near its upper end, said flanges and the opposing portions of the said closed wall being internally threaded to form aligned sockets 25 for the reception of threaded pipe sections, the body of the flask between the closed end and neck being unobstructed and constituting a sediment receptacle, and the flask as a whole constituting a substitution for an ordinary T.

In testimony whereof I have affixed my signature, in presence of two witnesses.

DON CURTIS LUCE.
